ATTORNEY.

UNITED STATES PATENT OFFICE

MILTON ALDEN, OF SPRINGFIELD, MASSACHUSETTS, ASSIGNOR, BY MESNE ASSIGNMENTS, TO RADIO INVENTIONS, INC., A CORPORATION OF NEW YORK

CONTACT TERMINAL FOR VACUUM TUBES

Application filed June 8, 1922, Serial No. 566,893. Renewed November 15, 1926.

This invention relates to improvements in sockets and particularly for use in connection with wireless apparatus in which the vacuum tube or amplifier is placed.

5 An object of the invention is to provide a socket structure having a series of resilient contact strips which are engaged by the terminals, or pins, of the tube when inserted in the socket. These contact strips are designed 10 to bend or yield so that all of the pins will be in good electrical contact with the resilient contact strips.

Heretofore it has been found in actual practise that the lengths of the pins on the tubes 15 vary so much that there is a possibility of one or more of these pins not engaging the resilient contacts in the socket with the result that there is an open circuit leading to the tube.

It has also been discovered that the extreme lower ends of the contact pins often 20 have a considerable quantity of solder thereon. This results from the fact that these pins are formed from small sized tubes which are normally open at their lower ends. The solder which is on the lower ends of the pins 25 comes from the operation of soldering the wire terminals of the tubes in these pins. This results in unequal lengths of the pins 30 as well as in unequal electrical contacts between the pins and the resilient contact strips.

It should also be observed that when a vacuum tube is inserted in the socket, and turned, the sides of the contact pins will engage and 35 rub against the overhanging part 10 of the contact strip 12 with considerable pressure, with the result that the cut-out portion 9 of the strip permits the outer end of the strip to be slightly twisted, or bent into an inclined 40 plane as the tube is turned.

By providing a wiping or rubbing contact between the sides of the pins and the upturned part 10 of the contact strips a positive and good electrical contact always results. In 45 case of the contacts becoming oxidized it is only necessary to slightly oscillate or partially rotate the tube a few times in its socket in order to produce a bright clean contact again between the sides of the pins and the upwardly 50 extending part of the strips.

The present invention, broadly comprises a resilient contact strip which is formed with an upwardly extending bent inner end portion the contact face of which is set inward from the edge of the body portion of the strip. 55 This inward set portion is provided with a curve or bend that produces this inward position of the part of the upwardly bent portion of the strip, whereby the contact strips are engaged by the sides of the pins of the tubes. 60 This bent portion will always make contact on the side of the pin of the tube if it does not on the end of the same, when the tube is inserted in the socket.

Referring to the drawings:

Fig. 1 is an end and side view of a portion of one end of a vacuum tube showing the usual four pins projecting from its lower end.

Fig. 2 is a partial sectional view of the socket showing the resilient fingers secured thereto.

Fig. 3 is a bottom view of Fig. 2 looking from the right showing the four resilient contact strips or fingers secured in place.

Fig. 4 is a plan view of one of the contact strips or fingers removed from the socket.

Fig. 5 is an end view of Fig. 4 looking from the right hand.

Fig. 6 is a perspective view on one of the resilient contact fingers showing the recessed portion and the upwardly extending integral part.

Fig. 7 is a side elevational view of Fig. 4.

Fig. 8 is a detail view showing one of the pins of a vacuum tube engaging the inner surface of the upwardly extending part of one of the contact fingers, and

Fig. 9 is a detail view showing a finger with two leaves.

Referring to the drawings in detail:

1 designates the lamp socket as a whole, having an opening 1' to receive the vacuum tube, and having a bayonet joint slot 2 formed in the side thereof to receive the pin 3 on the base-part of the tube. The tube, a portion only of which is shown, is indicated as a whole, by the numeral 4. This tube is formed with the usual projections or contact pins 5, four of which are shown. These pins are designed to make electrical 1

contact with the elastic contact strips or fingers that are attached to the base part of the socket. These fingers are indicated by the numeral 6 and are formed with an opening 7 which receives the attaching bolt 8. Each of the fingers 6 is held in fixed relation to the socket by one of the bolts 8, and further is firmly held in fixed relation to the socket by being positioned between two ribs 13, Figure 3. These fingers are also formed with a cut-out or recessed portion 9 to increase their flexibility and with an upwardly extending part 10 which is integral with the main body part 6 of the fingers. This upwardly extending part is connected to the part 6 by the bent or curved portion 11, whereby the inner surface of this upwardly extending part 10 stands in a plane slightly inward from the outer edge 12 of the strip and bent portion 11.

There are four of these fingers in the socket which corresponds with the four pins 5 of the tube 4. They are arranged 90° apart, as shown in Fig. 3. When the tube 4 is inserted in the socket the ends 5' of the pins 5 will engage the fingers 6 as shown in Figs. 6 and 7 which will force the resilient fingers downward into the dotted line position indicated at 6' in Fig. 8. When the tube is inserted it is given a slight rotary movement to bring the locking pin 3 into the seat of the bayonet slot 2. This operation brings each of the pins 5 against the inner surface of the upwardly extending part 10 with a result that contact is made with this upwardly extending part as well as at the ends of the pins 5 but should the ends 5' of one or more of these pins 5 not engage the fingers 6 then the sides of the pins 5 would strike the inner surface of the upwardly extending part 10 and make electrical contact therewith as indicated at 5" (see Fig. 5). The upwardly extending part 10 is now bent into the dotted line position 10'. This construction therefore renders a good electrical contact between the pins 5 and all of the fingers 6.

The contact fingers 6 are arranged staggered with their center lines substantially tangential to the circle passing through the axes of the tube prongs and with their inner ends overlapping or offset. The side contacts 10 press against the sides of the prongs. They thus resist the rotation of the tube as it is inserted with pin 3 in slot 2 and they tend to rotate the tube backwardly. This backward rotative tendency is prevented by the usual recess in the inner end of the usual bayonet slot 2.

The position of the parts 10 are such that they will all be simultaneously forced into the dotted line position 10' shown in Fig. 5 as already stated.

From this description will be seen that I have provided a socket construction for receiving a vacuum tube or detector of a wire-

less outfit without any liability of any of the circuits being left opened when the tube is inserted and rotated in the socket, since the sides of all of the pins 5 will engage the sides of the upwardly extending portions 10 which are located within the marginal edge 12. The recessed parts 9 permit the fingers to readily bend or yield when the pins 5 engage the same.

The reference numeral 5³ in Fig. 5 indicates the position of a pin 5 when in place.

It should also be stated that should some of the pins 5 be wrongly positioned the flexible upwardly extending parts 10 would still be engaged by all of the pins 5.

It should be stated that when the tube 4 is inserted in the socket 2 the sides of the pins 5 will have both a wiping and a rubbing or sliding contact with the flexible contact strips or fingers 6. There will be a wiping contact between the ends of the pins 5 and the flexible fingers and, also a wiping contact on the inner surface of the upwardly extending portions 10 by the pins 5 when the tube 4 is rotated in the socket 2. A rubbing or sliding contact will occur between the sides of the pins 5 and the inner surfaces of the upwardly extending portions 10. This sliding contact is brought about as the tube is pushed into the socket and then rotated to lock it in the socket. It will therefore be seen that there is both a wiping and a rubbing or sliding contact between the pins 5 and the upwardly extending portions or in other words there is a dual contact. The cut out portion 9 permits the portions 10 and the fingers 6 to be twisted when the tube is rotated in the socket.

In Fig. 9 is shown a contact finger which is composed of two thin resilient leaves 6' and each leaf may therefore be made of thinner material than if the contact finger is of single thickness. The leaves 6' are held in fixed relation to each other and to the socket by the bolt 8 and ribs 13, Figure 3, in the same manner as the single leaf contact 6 is held in position.

In other words there is greater resilient flexibility when two layers are employed than when only one is employed. The inner surface of the upwardly extending portion 10, as shown, overhangs the part 6. This construction is not necessary as the pins 5 would engage this portion if it did not overhang the part 6 in the exact position shown.

The curved part 11 which connects the upwardly extending part 10 with the part 6 of each finger permits the part 10 to readily flex or bend when one of the pins 5 is given a rotary movement against the part 10. The part 10 as shown, is located in a plane that is substantially at right angles to the plane of the part 6 of the finger.

What I claim is:

1. An electrical contact device for vacuum

tubes comprising a member having an opening at one end for attaching the same to a support, and an offset part against the side of which a pin on the tube engages for the purpose described the body portion of the member being formed with a cut out part adjacent the off set part to permit the part to yield when a vacuum tube is inserted.

2. A socket construction having an opening 10 to receive a vacuum tube having contact pins thereon, a plurality of contact strips in the opening of the socket and designed for engagement by the extreme lower ends of the pins, and each strip having a bent part which 15 is designed for engagement with the sides of the pins of the tubes in addition to the engagement of the ends of the pins, when the tube is inserted and rotated in the opening of the socket, as described.

20 3. A device for the purpose described comprising a strip of resilient material having an integral portion offset from one side of the main body part of the strip, the offset portion being connected to the main body 25 part by means of an inwardly extending curved part for locating the inner surface of the offset portion over the main body part of the strip and against which the sides of a pin of a vacuum tube presses and rubs when 30 inserted in a socket and turned.

4. A socket device comprising a tubular member for receiving a vacuum tube having contact pins thereon, contact fingers on the member for engagement by the extreme inner 35 ends of the pins and said fingers each having an offset portion which is designed to be engaged by the sides of each of said pins in addition to the engagement by the ends of the pins to provide both a wiping and sliding 40 contact between the ends and sides of the pins and the contact fingers when a tube is inserted and turned in the socket.

5. A contact strip for a vacuum tube socket comprising a body portion and a contact portion which is arranged at an angle to the body portion of the strip, said body portion being provided with a cut-out part in one edge adjacent the said contact portion.

6. A socket construction having an opening 50 to receive a vacuum tube having contact pins thereon, a plurality of contact fingers extending inwardly into the socket opening and designed for engagement with the lower ends of the pins, and upwardly extending 55 portions on the contact fingers adjacent the ends thereof and disposed at an angle, said upwardly extending portions being constructed and arranged for engagement with the sides of the contact pins when the tube is 60 turned in the socket.

7. A socket construction having an opening 65 to receive a vacuum tube having contact pins thereon, a plurality of contact strips disposed in the opening in the socket and designed for engagement with the ends of the

pins when the tube is inserted in the socket and upwardly extending portions carried by each contact finger and arranged at an acute angle to the body portion of the contact finger, said upwardly extending portions being 70 disposed in the path of rotation of the tube for engagement with the sides of the pins only when the tube is turned in the socket.

8. The combination with a contact carrier; of a socket for receiving the contact carrier, the contact carrier and socket being provided with laterally disposed complementary bayonet projection and channel formations; four contact pins circumferentially spaced 80 and projecting from the base of the contact carrier; and four correspondingly spaced spring members assembled with said socket and each comprising two leaf contact portions integrally formed from one piece of sheet metal, a broad face of one of these contact portions engaging the extreme end of a contact pin and a broad face of the other engaging one side of a pin and exerting pressure thereon laterally thereof.

9. A vacuum tube socket comprising an insulating base, four independently mounted spring contact arms secured thereto and having longitudinally extending contact portions at their inner ends adapted to engage the sides of the prongs of a tube and yieldable laterally and longitudinally of the socket when a tube is inserted, said arms extending substantially tangentially, opposite arms being substantially parallel and offset on opposite sides of a diameter of the socket.

10. A vacuum tube socket comprising an insulating base, independent spring arms carried thereby and insulated from each other and provided with portions yieldable longitudinally of the socket with contact tips yieldable transversely of the axis of the socket for engaging the sides of the prongs of a tube, means for limiting the incursion of the tube and its prongs and means positively limiting the rotation of the tube with respect to the base of the socket.

11. A socket having contact devices for engaging the electrodes of an insertable device, the electrodes of the insertable device including pins extending longitudinally of its axis, each contact device comprising a spring member having a portion yieldable longitudinally of the pin for engaging the end of the pin and another spring portion for engaging the side of the pin yieldable laterally of the pin and means for limiting the movement of the insertable device when the pins are in engagement with the contact devices.
